COLLAPSIBLE MOP

Oscar A. Flagstad, Minneapolis, Minn.

Application May 1, 1946, Serial No. 666,500

6 Claims. (Cl. 15—148)

1

This invention relates to improvements in cleaning and polishing elements such as used for mopping and polishing floors, cleaning walls and woodwork and like operations about the home. While the device according to my invention will have all such uses it is hereininafter termed merely a mop as a convenience in description.

The present invention relates more particularly to improvements in the mop disclosed in my prior U. S. Patent No. 1,802,889 issued April 28, 1931, and the primary object is to provide a mop which is simpler and less expensive in construction and assembly, more conveniently operated and used, and neater in appearance. Another object is to provide a mop in which the cleaning element itself is more readily and positively attachable to the frame and which is so constructed as to allow the use of the very desirable yarn type of cleaning element rather than only the common rag type as used in my previously patented mop. Another object is to provide an improved mop assembly which will greatly facilitate the cleansing or washing of the mop element. Still another object is to provide a waxing attachment for the mop which is simple, inexpensive and convenient and makes the single mop head or frame useful not only for wet mopping, dry or dust mopping but also for waxing.

These and other more detailed and specific objects will be disclosed in the course of the following specification, reference being had to the accompanying drawings, in which—

Fig. 1 is a side elevation of my improved mop in working position, and showing a dry or dust mop element.

Fig. 2 is a plan view but illustrating a wet mop.

Fig. 3 is a side elevation showing the mop of Fig. 2 in a folded or collapsed position and illustrating the manner in which the wet mop element, after being cleansed, may be wrung out through the squeegee rollers of a mop pail.

Figs. 4 and 5 are plan views, on a reduced scale, of the dry and wet mop elements respectively, removed from the mop head or frame.

Fig. 6 is a vertical cross sectional view through one end of the mop along the line 6—6 of Fig. 2.

Fig. 7 is a side view of the mop, using the wet mop element, illustrating its washing action in connection with a mop pail, the pail being shown partially in section and partially in elevation.

Fig. 8 is a fragmentary side elevation, partially

2

broken away and in section, of a waxing attachment for my mop.

Referring now to the drawing more particularly and by reference characters I show therein 5 a mop comprising a handle 10 upon the lower end of which is clamped a bracket device made up of opposed socket forming bracket members 11 shaped to fit opposite sides of the handle and clamped together thereupon by screws 13 passing through outwardly turned ears 14. The lower ends of the members 11 have wide outwardly turned ears or plates 15 through which screws or rivets 16 are passed to hold them together. The lower edges of the ears are rolled 10 to form loops or beads 17 forming pivot bearings for the inner adjacent ends of a pair of oppositely disposed rectangular wire frames 18. The side bars of the frames 18 are connected by comparatively thin metal plates 19 the ends 15 of which are rolled around the frames, as indicated at 20, fastening the plates adjacent the inner ends of the frames.

Outwardly of the plates 19 narrow strips 21 are also secured across the frames 18 and are 25 rolled at their ends at 22 about the side bars thereof. The edges of the strips 21 next to the plates 19 are formed with beads 23 for anchoring cross pins 24 and further are extended in the form of the ears 25 over the plates 19 and 30 riveted thereto at 26 to permanently anchor these parts together. Jogs or offsets 27 (Fig. 2) formed in the side bars of the frames 18 then serve to hold the assemblies at the inner 35 ends of the frames against the outward pull of the mop element when it is applied to the frames.

The lower ends of a pair of links 28 are pivotally attached at the centers of the pins 24 and 40 the upper ends of these links are positioned between and pivoted upon cross bolts or pins 29 connecting the ends of a pair of cross arms or equalizers 30. A pin 31 joins the centers of the arms 30 and passes loosely through slots 32 in the opposite sides of the bracket device, said slots being formed by properly spacing the adjacent edges of the members 11. The arms 30 45 may rock upon the pin 31 and the pin may move up and down in the slot, it being understood that the lower end of the handle 10 terminates slightly above the upper ends of the slots 50 32 to clear the pin.

The pin 31 and cross arms 30 are vertically adjustable, or positionable in a direction lengthwise of the handle, by a pair of links 33, at opposite sides of the handle axis, pivotally secured 55 at their upper ends to the extremities of the pin

31 and at their lower ends pivotally attached at 34 to a pair of levers 35. The lower ends of the levers 35, below the pivots 34, are pivotally attached at 36 to brackets 37 secured on one side of the outwardly extending ears 15, by the aforesaid screws or rivets 16. The upper ends of the levers are rigidly connected at 38 to the ends of a yoke member 39 which is shaped to and normally straddles the handle 10 above the tangs 11.

The foregoing mechanism comprises the mop head or frame and is used in connection with a rectangular, elongated cleaning element or mop per se, which for use as a dry or dust mop comprises a fabric backing strip 40 of a length such as to fit endwise beneath the wire frames 18 and up over the outer ends thereof back beneath the plates 19. The width of this strip or backing 40 may be slightly less than that of the frames 18 and adjacent its ends the strip has cross loops, straps or looped tabs 41 sewed in place adapted to slide over the side bars of the frames and hold the backing to the frames near their outer ends. The plates 19 have transversely extending slots 42 and the end extremities of the backing strip 40 are gathered in and looped around anchor pins 43 having looped and widened ends 44 to hold them in place, as clearly shown. The arrangement is such that in placing the cleaning element on the mop head these pins 43, and of course the attached ends of the backing 40 may be worked up through the slots 42 and the widened ends 44 of the pins will then oppositely overlie the margins of the slots to firmly hold the cleaning element in place. On the other hand, and by suitable manipulation, the pins 43 may be worked down through the slots to release the cleaning element.

The backing strip 40 has yarn ends or thrums 45 sewed into its intended lower side for the usual purpose and as best seen in Figs. 1-4 these yarn thrums extend also up and around one end of the mop to facilitate certain cleaning operations.

For wet mopping I also provide a mop element 46 in the form of a piece of suitable length and shape of very coarsely woven fabric, provided with tabs or sleeves 47 to engage the sides of the frames 18 as previously described looped at its ends around pins 48 identical to the pins 43. This mop element may be readily substituted for the dry mop element whenever desired, as will be apparent.

In use with either mop element and with the levers 35 swung upwardly to the position of Fig. 1 the cross arms 30 will be forced upwardly holding the frames 18 in outwardly projecting or outspread positions. When force is exerted on the handle 10 then the inner ends of the frames 18 will be pushed down (Fig. 1) providing substantially even pressure the full length of the mop as it is used. It will be noted that the pivots 34 in this working position of the mop, with the yoke 39 engaging handle 10, move slightly past dead center position with respect to the pivots 36 and 31 so that the mop will maintain such position under all usual conditions. The mop handle may, as will be readily apparent, be swung to any angle while the mop is in use.

To clean the mop, either by shaking it in the case of a dust mop or by washing and wringing it in a mop pail when the wet mop is being used, the yoke 39 is grasped and pulled out causing the links 33 and levers 35 to unfold and allowing the frames 18 to fall or swing downwardly at their

outer ends as seen in Fig. 3. The mop element then hangs in a loose loop with all but its ends free for manipulation as it is cleaned.

My present mop has a distinct advantage in that thorough washing of the mop element is greatly facilitated by a novel action of the mop frame as will now be described. Referring to Fig. 7 I show the mop with the wet mop element 46 loosened and dropped into the water in a conventional mop pail 49. Said pail has the usual fixed roller 50 and movable roller 51 forming a wringer for the mop, the latter roller normally standing well away from roller 50 but being movable theretoward by the usual foot treadle mechanism 52. In washing the mop the levers 35 are rested upon the roller 50 with the yoke 39 hooked thereover and by then merely working the handle 10 up and down the levers 35 and links 33 will be actuated to alternately spread and close the wire frames 18. This results in a flapping, opening and closing action of the mop wings, as the frames 18 may be called, and an alternate folding and unfolding of the mop element 46 in the water as a result of which a thorough agitation of the element is obtained quite like that to which it might be subject in the ordinary clothes washer. All parts of the mop element are thus thoroughly and readily washed and at the completion of the washing the roller 51 may be moved over to engage the mop element just below the frame, as seen in Fig. 3, whereupon as the mop is pulled up the water will be forced out by the squeegee action of the rollers 53-51. It is thus seen that the levers 35 not only serve as means for folding and unfolding the mop but also as actuators for washing the mop element. Likewise the yoke member 39 acts not only as a stop for engaging the mop handle when the mop is in use but as a catch for holding the lever in place as the mop handle is moved up and down in washing the mop element.

In the case of the dry or dust mop, the mop element may be cleaned of accumulated dust and lint merely by shaking the mop in its unfolded position, causing the frames 18 to go through a "bird-wing" flapping action such as to beat the back of the mop element together and thoroughly clean it. Whenever necessary the dry mop element may also be thoroughly washed in the same manner as the wet mop and then hung up to dry and rewaxed or oiled for further use. Ordinarily a dry mop must be washed, if at all, in the clothes machine in order to thoroughly clean it and since most housewives do not like to do this, the mop is frequently discarded when washing is needed. However, due to the efficiency and convenience of my washing action as described above the mop may be very thoroughly washed in the ordinary mop pail and it is believed a substantial saving in expense and material will result.

It will be noted that I have in this invention provided a double equalizer mechanism having two arms 30 and connected links 33 and levers 35 as contrasted to the single corresponding elements of my prior Patent No. 1,802,889. Thus I attain more even distribution of pressure to the mop, particularly transversely, and prevent any tendency toward twisting of the parts.

The slots 42 for the ends of the mop elements 40 and 46 constitute socket means for the engagement of the lock elements or pins 43 and 48 on the ends of these mop elements. The arrangement is obviously such that a very secure fastening may be obtained and one which may be readily discon-

nected when necessary. It is contemplated that mop elements specially made for my mop will be furnished with the pins 43—44 attached thus insuring that the purchaser will obtain and use mops of the proper material to take advantage of the full efficiency of the mop and which will all properly fit the mop head, rather than to use makeshift mop elements which may be impractical or ill fitting.

Referring to Fig. 8 I show therein a waxing attachment which may be substituted for the mop elements 40 or 46 where waxing is to be done and which thus makes my mop frame even more versatile. This waxing attachment comprises a heavy metal plate 53 of a shape and size nicely to fit under the outspread frames 18 and provide sufficient weight for easy waxing. A wooden pad 54 of similar size is placed below the plate 53 and the ends 55 of a felt waxing cloth or the like 56, passing lengthwise beneath the pad 54, is gripped between the ends of the pad and plate. Screws 57 pass upwardly through the pad and plate and these parts may be firmly fastened together by nuts 58 in upper ends of these screws. The screws 57 further are so located that clips 59 may be placed on their upper ends and engaged over the frames 18 and drawn tight by wing units 60. Thus the waxer may be readily attached to, or detached from the mop head, and when not in use may be readily stored away and will occupy but a small space. Thus storage, as contrasted to the usual special waxer with its own handle and frame, is greatly facilitated, and the expense is likewise reduced.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A mop comprising a handle and a collapsible head for holding a cleaning element, a metal member secured to the handle and having an elongated slot opening through opposite sides, the said head comprising a pair of frames pivoted at adjacent ends to the end of the metal member for flapping motions in cleaning the cleaning element, a pair of spaced equalizer bars disposed at opposite sides of the metal member and a pin connecting said bars and slidably mounted through the said slot, links pivotally connected between the ends of the equalizer bars and pivoted to the said frames at points spaced from the ends thereof, and means for releasably holding the pin against movement lengthwise of the slot to thereby hold the frames against flapping motion when the mop is in use.

2. A collapsible mop head for a mop handle and for holding a cleaning element, said mop head comprising a metal socket member adapted to be secured to the mop handle and said member having an elongated slot extending lengthwise of and opening through opposite sides of the member, a pair of frames having means for connection to the cleaning element, means pivoting the frames to said socket member at the lower end thereof for swinging movements from substantially parallel to aligned positions with respect to each other, equalizer bars positioned at opposite sides of the socket member, a pin extending through and slidably in said slot, the said equalizer bars being mounted on opposite ends of the pin, links pivotally connected to the equalizer bars and pivoted to the frames at points spaced from the

spaced from the pivots of the latter, and locking means for locking the pin against movement lengthwise of the slot to hold the frames in substantially aligned positions when the mop is in use.

3. A collapsible mop head for a mop handle and for holding a cleaning element, said mop head comprising a metal socket member adapted to be secured to the mop handle and said member having a longitudinal slot opening through opposite sides of the member, a pair of frames for connection to the cleaning element, means pivoting the frames to said socket member adjacent the lower end thereof for swinging movements from substantially parallel to aligned positions with respect to each other, equalizer bars positioned at opposite sides of the socket member, a pin extending through and slidably in said slot, the said equalizer bars being mounted on opposite ends of the pin, links pivotally connected between the equalizer bars and pivoted to the frames at points spaced from the pivots of the latter, a lever pivoted to the socket member for swinging movements in a plane parallel to the motion of the frames, and means connecting the lever and equalizer bars for moving the latter and the attached links and swinging the frames.

4. A collapsible mop head for a mop handle and for holding a cleaning element, said head comprising a metal socket member adapted to be secured to the mop handle and said member having an elongated longitudinal slot opening through opposite sides of the member, a pair of frames having means for connection to the cleaning element, means pivoting the frames to said socket member adjacent the lower end thereof for swinging movements from substantially parallel to aligned positions with respect to each other, equalizer bars positioned at opposite sides of the socket member, a pin extending through and slidably in said slot, the said equalizer bars being mounted on opposite ends of the pin, links pivotally connected to the equalizer bars and pivoted to the frames at points spaced from the pivots of the latter, a lever pivoted to the socket member for swinging movements in a plane parallel to the motion of the frames, and links connecting the lever to the ends of the pin for moving the latter in the slot and swinging the frames.

5. In a collapsible mop head for a mop handle and having means for holding a cleaning element, a metal socket member adapted to be secured to the mop handle and said member having an elongated longitudinally extending slot opening through opposite sides of the member, a pair of frames, means pivoting the frames to said socket member adjacent the lower end thereof for swinging movements from substantially parallel to aligned positions with respect to each other, equalizer bars positioned at opposite sides of the socket member, a pin extending through and slidably in said slot, the said equalizer bars being mounted on opposite ends of the pin, links pivotally connected to the equalizer bars and pivoted to the frames at points spaced from the pivots of the latter, a lever pivoted at one end to the socket member for swinging movements at its other end in a plane parallel to the swinging movements of the frames, links connected to the pin and to the lever between the ends of the latter, and the lever having means at its said other end for engagement over a part of a mop bucket whereby endwise movements of the mop handle will swing the lever and through the

equalizer bars and links swing the frames for cleansing the cleaning element in said bucket.

6. A collapsible mop head for a mop handle and for holding a cleaning element, said mop head comprising a metal socket member adapted to be secured to the mop handle and said member having an elongated longitudinally extending slot opening through opposite sides of the member, a pair of frames having means for connection to the cleaning element, means pivoting the frames to said socket member adjacent the lower end thereof for swinging movements from substantially parallel to aligned positions with respect to each other, equalizer bars positioned at opposite sides of the socket member, a pin extending through and slideable in said slot, the said equalizer bars being mounted on opposite ends of the pin, links pivotally connected to the equalizer bars and pivoted to the frames at points spaced from the pivots of the latter, levers pivoted at one end to opposite sides of the socket member for swinging movements at their other ends in planes parallel to the motion of the frames, links pivotally connected to the opposite ends of the pin and to the levers, and a member connecting said other ends of the levers and shaped to fit partially around the mop handle.

OSCAR A. FLAGSTAD.
